UNITED STATES PATENT OFFICE.

FERNAND BOYER, OF PARIS, FRANCE.

ATTACHMENT TO CARPET-KNOTTING MACHINES FOR SHOOTING IN THE FILLING.

1,193,982.

Specification of Letters Patent.

Patented Aug. 8, 1916.

Application filed July 22, 1915. Serial No. 41,248.

To all whom it may concern:

Be it known that I, FERNAND BOYER, manufacturer, a citizen of the Republic of France, residing at Paris, in the Republic of France, have invented certain new and useful Improvements in Attachments to Carpet-Knotting Machines for Shooting In the Filling, of which the following is a specification.

10 The present invention relates to an attachment for shooting in the filling in carpet knotting machines where the knots are made on vertically running warps, and comprises means for forming a shed above a 15 row of knots immediately after the same have been tied, means for guiding a shuttle and means for moving a reed.

15 The annexed drawing represents two working examples of the invention, and for 20 sake of plainness, the means for knotting are not shown.

25 Figures 1 to 7 illustrate one form with a lower movable guide of the shuttle. Fig. 1 is a diagrammatic side elevation. Figs. 2 and 3 are partial front views. Figs. 4, 5 30 and 6 are views of details in different positions. Fig. 7 is a partial front view of a detail. Figs. 8 and 9 are diagrammatic views of the backing fabric. Figs. 10, 11 and 12 35 relate to a second form, without a lower, movable guide for the shuttle. Fig. 10 is an end view of the shuttle. Fig. 11 a partial side elevation. Fig. 12 a partial front view of the means for guiding the shuttle 40 and for moving the reed. Fig. 13 is a partial elevation and cross section on an enlarged scale illustrating the construction of the mechanism by which the reed is shifted out of its normal position during predetermined operations of the machine. Fig. 14 45 is an elevation and partial cross section of the reed, its frame, and associated parts taken at right angles to the position of these parts as shown in Fig. 13. Fig. 15 is a sectional plan on the line 1, 1, Fig. 13, and Fig. 16 is a partial elevation similar to Fig. 13, showing the reed, its frame and associated parts in their shifted positions.

50 Referring to Figs. 1 to 7, a frame 1 is provided at each side of the machine and supports the bearings for all the shafts and lever arms. Warp α unrolling from a warp beam 30 mounted outside of the machine, is guided over a lathe 31 and beam 32 toward 55 the reed 23 and is furnished at γ (Fig. 5) with the filling and with knots so as to

form a carpet. Thence the finished carpet runs over a roller 33 on a shaft 35 to a beam 34 outside of the machine, where it is rolled up. 60

The means for shooting in the filling, for moving the reed and for forming the shed, and the means for guiding the shuttle, are actuated from shaft 2, there being a cam disk 3 keyed thereon and provided with 65 grooves for guiding the parts for moving the reed and the lower guides of the shuttle. The reed 23 is provided with guide members for directing the path of the warp thread, the reed 23 being mounted between 70 two frames 24, the ends of which are secured by means of bolts 25 to links 22. These links are hinged to a rod 21 which connects two arms 20 keyed to a shaft 15 and are given a vertical rocking movement from an 75 angular lever 13, 14, by means of an arm 16 fast on a shaft 15, and by means of a connecting rod 17 which is provided at its ends with link connections 18, 19. The angular lever 13, 14, receives a rocking movement from a cam disk 3 on shaft 2. A curved 80 groove in said disk guides a cam roller provided at the end of an arm 4 keyed to the same shaft 5 where is keyed also an arm 6. This arm is hinged at its end to a rod 7, 85 said rod engaging with a hook a pin held by the forked end of the arm 13 of angular lever 13, 14.

In order that the movement and travel of the reed may be accurate the links 22 90 carrying the reed 23 and reed frames 24 are guided sidewise by friction rollers 29 running in guide bars 28 normally maintained in a vertical position. These guide bars 28 are pivotally connected by a pin 28^a 95 in the extremity of a strut 27 connected to and depending from a girder 26 which is supported by and extends between the frame members 1. The strut 27 is braced by auxiliary struts 27^a extending from the lower 100 end of the strut 27 to the frame members 1. The guide bars 28 are connected to the cam disk 1 through an adjustable connecting rod e , a bell crank lever f , g , a link h , and a bell crank lever i , k . These parts are operated just prior to the time when the knotting process takes place, that is, when the pile threads are tied around the warps, so as to swing the reed and the frames carrying the same from their normal positions 105 as shown in Fig. 13 to the positions these parts assume during the knotting process as

- indicated in Fig. 16, in order that these parts may not interfere with the operation of the knotting mechanism. After this by the same link and lever mechanism the guide bars are returned to their normal vertical positions in order that when the links 22 are reciprocated a vertical reciprocating movement or travel may be imparted to the reed and the frames carrying the same.
- 13 The connecting rod 7 may be hooked into or out of engagement with the angular lever 13, 14, whenever the reed has to be moved or to be set at rest. Said rod however is worked in connection with a rod α which is actuated 15 from a shaft for imparting movement to the knotting tools and for moving the reed in connection therewith, as shown and described in my copending application Serial No. 864,221, filed September 30th, 1914.
- 20 Rods α and 7 are guided near their hooked ends within slots and between friction rollers 8, 8, provided on two parallel links 9, 10, said links forming with the two armed lever 12 and two arms of a three armed lever 11, a 25 hinged frame shaped like a parallelogram which is worked by the third arm of lever 11 in such a way that if either one of the rods is disconnected from the pin on the arm 13 the other rod will be connected thereto.
- 30 In order to obtain a backing fabric as is represented in Figs. 8 and 9, a woof thread α has to be shot into the warp α , and to do this a shuttle-box 36 is attached to the outside of each frame. A shuttle 37 is indicated 35 in Figs. 2 and 3. The woof thread runs from a spool 38 inside the shuttle (Figs. 7, 10, and 12) across the bottom of the body of the shuttle to its outside. For forming the shed, each warp thread α runs through 40 the eye of a heddle 39, which heddles are arranged horizontally in two horizontal rows, an upper and a lower row, at the rear of the warps, and are held fast within two flat straight bars 40 (Figs. 1, 4 and 6) attached 45 at right angles rigidly to the ends of the horizontal slide bars 41 which are guided within brackets 42 (Figs. 1 and 3), fast to a cross beam 43 connecting the frames 1. The slide bars 41 are provided with racks 44 50 which engage pinions 45 one of the same being on each side of the machine and keyed to a shaft 46 running through the whole machine. These pinions being placed each between an upper and a lower bar are adapted 55 to move bars simultaneously but in opposite directions. The shaft 46 is journaled in the brackets 42 within the side frames 1 and projects at one end outside the frame. At one end exteriorly of the frame, the shaft 46 carries a pinion 47 engaging a toothed segment 48 journaled on a pin 49 fast to the frame. An oscillating movement is imparted to the 60 brackets 42 from the driving shaft 2 by means of a set of spur wheels 51, 52, and a 65 two armed lever 55, 56, which is journaled

on a pin 54 fast in the frame, one arm of said lever being connected by a rod 57 to a forked arm 50 of the segment, while its other arm is fitted with a friction roller and is guided thereby in a groove on one side face of the 70 spur wheel 52, which is journaled to a pin 53 supported between a bracket and the side frame. When the driving shaft 2 turns, the lever 55, 56, will be oscillated and this movement will also be imparted to the segment 48 75 and to pinions 45 and thereby the bars 41 and the needles 39 will be caused to reciprocate, the upper bars advancing, while the lower are retreating, and vice versa. The warp threads α therefore which alternately 80 run through an upper and through a lower heddle will be swung as indicated in Fig. 4 part into a position α' and part into a position α'' , which positions will be reversed into a position as indicated in Fig. 5, and again 85 into the position of Fig. 4, for each oscillation of the pinions 45, and sheds will thus be formed for shooting in the filling or the woof. To this end the shuttle box 36 is 90 fitted with a shuttle driver 58 made of suitable material, as for instance of leather, which in its starting position bears against the shuttle 37 (Fig. 2) and is engaged through a slot by the upper end of a picking stick 59, the lower end of which is held fast 95 within a picking lever 60. This latter is rigidly fixed on a pin 61 journaled within a bracket 62 attached to the frame 1 and is adapted to be pulled back again after each throw of the shuttle into the position illustrated in Fig. 2, by means of a spring not shown in the drawing, but which is attached to the pin 63 at the lower end of said lever. Within the same bracket 62 another pin 64 100 is journaled somewhat behind the pin 61 and projects to the right side of said bracket, as viewed in Fig. 1, where it is also journaled in an auxiliary bracket arm 65. This pin 64 carries at its projecting end and set crosswise a pin with journaled roller 66 and between the two arms of the bracket 62 a downwardly set forked lever 67 (Figs. 1 and 3). Journaled roller 66 in the starting position bears against the hub of a wiper 68 105 which is rigidly fast to the shaft 69 running along the whole machine and driven in the direction of the arrow in Fig. 1 from the driving shaft 2 by a gear not shown in the drawing. At each end of this shaft and on both sides of the machine such a wiper 68 is provided, but the two are set at an angle of 110 180° to each other.

Opposite to the bracket 62 on the inside of the frame 1 a bracket 70 is bolted fast to the frame with bearings for a shaft 71 (Figs. 1 and 3) and two arms are keyed on to this shaft, a downwardly set arm 72 fitted with a sharp edge and an upwardly set arm 73 fitted with a clutch for clamping a belt 74 connecting said arm to the picking-lever 60 115 120 125 130

and fitted also with a stop 75 resting there-
with against an adjustable stop bolt 76
owing to the springy pull exerted in the di-
rection of the arrow in Fig. 3, by the re-
5 treated picking lever 60. A rod 77 kept in
constant contact with the sharp edge at the
end of the arm 72 owing to the pull of a
spring 79 which connects the one end of said
rod with a stud fast to bracket 70 is linked
10 with its other end to the forked part of lever
67 and engages with a shoulder 78 the sharp
edge of arm 72. On the end of the link bolt
where lever 67 meets rod 77 there is also
15 provided a knob 80 which is attached to the
frame by a spring not shown in the drawing,
for the purpose of maintaining a constant
pull on lever 67 toward the frame.

Whenever the shaft 69 is turned in the
direction of the arrow, the wiper 68 will lift
20 roller 66 which will cause lever 67 to swing
outwardly together with rod 77. Shoulder
78 which when at rest is at some distance from
the sharp edge of arm 72 will strike against
25 it (Fig. 3) and will swing arm 73 so as to
give a short pull on belt 74 whereby picking
lever 60 and picking stick 59 will be caused
to strike rapidly in the direction of the ar-
row in Fig. 3, sending the shuttle 37 through
30 the shed which has been opened in this very
moment and sending it farther into the op-
posite shuttle box 36, where a similar action
takes place owing to the wiper 68 set at an
angle differing by 180° from the direction of
35 the first wiper. After each stroke the pick-
ing stick 59 will again assume the starting
position according to Fig. 3, but only during
the intervals between the engagements be-
tween roller 66 and wiper 68.

In order to produce a sufficient velocity
40 of the shuttle, the shaft 69 has to turn
rather rapidly and then too little time may
be left to the shuttle 37 for its movement be-
cause the wipers set at an angle of 180°
45 from each other would move the opposite
picking sticks before the shuttle will have
reached the shuttle driver 58 at the outer
end of the shuttle box. An interrupting de-
vice has therefore been provided which
50 brings shoulder 78 some times out of the
path of the sharp edge of arm 72. This
may be done by the two armed lever 82, 83,
pivoted on a pin 81 fast to the inside of the
frame. Arm 82 of this lever rests above rod
55 77 (Figs. 1, 2 and 3) and arm 83 is linked
by a rod 86 to an arm 85 pivoted on a pin 84
fast to the frame and fitted at its middle
part with a sliding piece 87 (Fig. 1). An
arm 85 rests by means of this sliding piece
60 on a curve 88 provided on the hub of gear
wheel 52 which turns in the direction of the
arrow indicated thereon and will therefore
allow the engagement of the shoulder 78
with the sharp edge of the arm 72 and there-
65 by also the throw of the shuttle only during
the moments when sliding piece 87 has sunk

into the hollow of said curve 88 (Fig. 1).
At any other moment arm 85 will be lifted
again and thereby arm 82 will be caused to
throw shoulder 78 out of the path of the
sharp edge of arm 72. All these operations
70 are very similar to the usual weaving opera-
tions. In the present case however the dif-
ference exists in the lower guiding means of
the shuttle. In the ordinary looms the warp
runs horizontally and the shuttle moves on a
75 lathe which supports the same even during
the travel. Here such a stationary lathe is
impossible because the filling z has to be
beaten up against the finished part (Figs. 4
and 5) at y . Therefore movable battens
80 have been provided which support the shut-
tle and are withdrawn again therefrom at
suitable moments. Small guide plates 90
are fixed on two straight bars 89 (Figs. 2, 4
and 7) whereof one is before and the other
85 behind the warps and said bars are support-
ed on each side of the machine inside of the
frame by arms 91 pivoted on pins 92 of cross
heads 96 and are guided by means of fric-
tion rollers 93 attached to said arms which
90 roll within the curves 94 of guide pieces 95
fixed to the frames.

Each cross head 96 is seated on the top of
a rod 97 (Figs. 1, 3 and 4) which is adapted
to slide up and down within a guide piece
95 98 fast to the frame. This movement is
caused by an angular lever 100, 101, which
engages by a slot in one of its arms a jour-
naled roller 99 provided on the said rod and
further engages by a friction roller fitted
100 to its other arm a groove within the said
face of a disk 3 on the driving shaft 2 (Figs.
1, 2, 4 and 6). Thus guide plates 90 may
be easily brought into the upper positions
as indicated in Figs. 4, and 5, in order to
105 support the shuttle or into a lower position
as indicated by Fig. 6, in order to be with-
drawn from the path of the shuttle. Owing
to the shape of curves 94 said shuttle guide
plates 90 are brought nearer together or
110 moved apart according to need. As shown
in Fig. 5, these guide plates form the lower,
the warp x' and x^2 the lateral, and reed 23
the upper guides for the shuttle 37.

As shown in Figs. 2, 3 and 7, the shuttle
115 is received on both sides of the opened shed
by the extension boxes 102 (Figs. 2, 3 and 7)
of the shuttle box 36. As soon as the shut-
tles have left the shed x' , x^2 , the guide plates
90 drop into the position shown in Fig. 6,
120 whereupon the filling will be beaten up
against the finished carpet.

The manner of working aimed at by the
invention is now as follows: While the ma-
chine by means not shown is introducing at
125 the point y of the warp a row of knots the
reed 23 will be in the position shown in Fig.
16 while the heddles 39 and the guide plates
90 are in the position shown in Fig. 6, and
the shuttle 37 is ready to be thrown from
130

the shuttle box 36 (Fig. 2). After the knots have been introduced the shafts 2 and 69 will be moved, whereby at first the heddles 39 are moved from the position shown in Fig. 6 into that shown in Fig. 4 by means of the lever 55, 56, link 57, segment 50, pinions 45, 47, on the shaft 46, and the toothed disk 52, and then the reed and guide bars are returned to the positions shown in Figs. 1, 4, 5 and 13 by the link *e* and the parts associated therewith as hereinbefore described. Simultaneously the guide plates 90 have been moved from the position shown in Fig. 6 into the position shown in Fig. 4 by means of the cam disk 3. The picking stick 59 will therefore strike in the direction of the arrow, Fig. 3 and will send the shuttle through the opened shed (Fig. 7) into the opposite shuttle box whereby the woof thread *z* on the spool 38 will unwind. As soon as the shuttle 37 has passed the guide plates 90 these latter will drop again into the position shown in Fig. 6 and the reed 23, owing to the action of the cam disk 3, will move to beat up the filling *z* at the point *y* of the warp. Simultaneously the heddles 39 will move from the position shown in Fig. 4 into that shown in Fig. 5, and will cross the warps above the woof thread just shot in. The reed 23 and the guides 90 now rise and the shuttle 37 is then thrown back again into the starting shuttle box. The woof thread *z* is again beaten up at the point *y* of the warp in the same way as explained above and the whole process will be repeated until another row of knots has been introduced. The woof thread however may also be shot in without employing the lower guiding means, as hereinbefore described. This may be done by the mechanism represented in Figs. 10, 11, and 12. The shuttle 37 then has a cross section, as illustrated at 103, in Fig. 10, so that it almost fills up the opened shed *x*, *x*². Shuttle box 36 and its extension 102 and also the shuttle driver 58 will then have to be modified in form accordingly, but the working remains the same as shown and described for the preferred form illustrated in Figs. 1 to 7.

I claim as my invention:

1. In a carpet weaving machine in which the warps move vertically and in combination, a mechanism for forming a shed in the warps, devices for actuating the said mechanism, a reed, devices for imparting a vertical movement to said reed, guide members for the shuttle, and means for moving said guiding member for the shuttle to and from the position in which it directs the movement of the shuttle.
2. In a machine for weaving carpets in which the warps move vertically, and in combination, parallel straight bars, guide plates fixed thereto, one of said parallel straight bars lying on one side of the warps

and the other on the other side of the warps, and means for moving said parallel straight bars to position to guide the shuttle when thrown and remove said parallel straight bars from said position when the wefts are beaten to position between the warps. 70

3. In a machine for weaving carpets in which the warps move vertically, and in combination, a reed, devices for vertically moving said reed, movable guides for directing the path of the devices for moving said reed, and means for moving said guides into and out of their operative positions. 75

4. In a machine for weaving carpets in which the warps move vertically and in combination, a frame, a reed mounted in said frame, links connected to said frame, means for imparting a vertical movement to the said links so that said reed is moved correspondingly, movable guides for maintaining the said links in a predetermined path during the travel thereof, and means for moving said guides into and out of their operative positions. 80

5. In a machine for weaving carpets in which the warps move vertically, and in combination, a frame, a reed mounted in said frame, links connected to the said frame, means for imparting a vertical movement to the said links and consequently a corresponding movement to the said links and reed, guides for maintaining said links in a predetermined path during the travel thereof, mechanism for forming a shed in the warps, devices for actuating the said mechanism, and means for throwing a shuttle to properly place the wefts within the warps. 90

6. In a machine for weaving carpets in which the warps move vertically, and in combination, a frame, a reed mounted in said frame, links connected to the said frame, means for imparting a vertical movement to the said links and consequently a corresponding movement to the said links and reed, guides for maintaining said links in a predetermined path during the travel thereof, parallel straight bars, heddles fixed on said parallel straight bars in rows one above the other and adapted to engage alternate warps, slide bars fitted with racks and secured to said straight bars, pinions each placed between every pair of upper and lower slide bars so as to engage the racks thereof, means for turning said pinions to move said parallel straight bars in opposite directions, so as to cause the heddles to form the sheds in the warps, devices for guiding a shuttle through its travel through the shed, and means for moving said devices into and out of their operative positions. 105

7. In a machine for weaving carpets in which the warps move vertically, and in combination, a frame, a reed mounted in said frame, links connected to the said frame, 110

means for imparting a vertical movement to the said links and consequently a corresponding movement to the said links and reed, guides for maintaining said links in 5 a predetermined path during the travel thereof, parallel straight bars, heddles fixed on said parallel straight bars in rows one above the other and adapted to engage alternate warps, slide bars fitted with racks and 10 secured to said straight bars, pinions each placed between every pair of upper and lower slide bars so as to engage the racks thereof, means for turning said pinions to move said parallel straight bars in opposite 15 directions, so as to cause the heddles to form the sheds in the warps, other straight bars, one being placed in front of the warps and the other behind the warps, guide plates secured to said other straight bars, and means for moving said other straight bars and 20 guide plates to position to direct the travel of the shuttle when thrown and also to withdraw the said other straight bars and guide plates from the position in which they direct the travel of the shuttle when the said reed 25 is moved to beat the wefts to position between the warps.

In testimony whereof I have affixed my signature in presence of two witnesses.

FERNAND BOYER.
